UNITED STATES PATENT OFFICE.

VACLAV SPEVACEK, OF TRAVERSE CITY, MICHIGAN.

TAILOR'S SQUARE.

1,123,031.

Specification of Letters Patent. Patented Dec. 29, 1914.

Application filed March 17, 1913. Serial No. 754,897.

To all whom it may concern:

Be it known that I, VACLAV SPEVACEK, a citizen of the United States, residing at Traverse City, in the county of Grand 5 Traverse and State of Michigan, have invented certain new and useful Improvements in Tailors' Squares; and I do declare the following to be a full, clear, and exact description of the invention, such as 10 will enable others skilled in the art to which it appertains to make and use the same.

This invention relates to improvements in tailors' and cutters' squares.

One object of the invention is to provide 15 a square of this character having means whereby the inclination of the body of the person being fitted may be accurately determined and the clothing cut so that they will require a minimum amount of alteration 20 and adjustment when fitted.

Another object is to provide a square which will facilitate the cutting of a garment and the making of an accurate pattern.

25 A further object is to provide a square of this character which is reversible for obtaining measurements on both right and left sides.

With these and other objects in view, the 30 invention consists of certain novel features of construction, and the combination and arrangement of parts as will be more fully described and claimed.

In the accompanying drawings: Figure 1 35 is a perspective view of my improved square; Fig. 2 is a vertical longitudinal section thereof taken on the line 2—2 of Fig. 1; Fig. 3 is a horizontal section taken on the line 3—3 of Fig. 1. Fig. 4 is a 40 front elevation of my improved square in operative position; Fig. 5 is a rear elevation thereof; Fig. 6 is a similar view with the measured person shown in a stooping position; Fig. 7 is a fragmentary perspective view illustrating the manner in which 45 the two tapes are secured to the square.

My improved square comprises a main bar or blade 1 of suitable size and length and which has thereon near its upper end graduations 2 as shown. The upper end of the bar or blade 1 has its side faces rounded off slightly and has hinged thereto an upper member 3 which is disposed at a slight angle to the blade or bar 1 and is designed 50 for locating the shoulder point of the garment to be cut. The member 3 is hinged

to the upper end of the blade 1 in such manner as to permit said member 3 to swing in either direction as clearly indicated in dotted lines in Fig. 1 of the drawings. Along the inner edge of the member 3 is also arranged a graduated scale 4.

In the bar or blade 1 near its upper end is formed a transverse semi-circular aperture 5 in which is arranged a spirit level whereby the vertical position of the square may be ascertained. The blade 1 is offset on its inner edge a short distance from the upper end thereof as shown at 7 and through the blade and the offset portion 7 is formed a transverse slot 8 with which is slidably and adjustably engaged a right angular arm 9, said arm being adjustably secured in the slot 8 of the blade by a set screw 10 as shown. The offset edge 7 of the blade forms an increased bearing surface for the arm 9 which is slidably engaged with the slot 8. The arm 9 is provided with an outer section or member 11 which is hinged at its inner end to the arm 9 to swing in either direction and which is provided to indicate the depth of the scye or depth of the arm-holes of the garment.

Arranged on each side of the blade 1 near the inner edge thereof and immediately above the slot 8 are laterally projecting studs 12 to which are adapted to be attached tape measures for obtaining all short measurements. Also arranged on each side of the blade 1 a short distance above the lower end thereof are laterally projecting studs 13 with which are adapted to be engaged tape measures for obtaining seat and stomach measurements as will be readily understood by those skilled in the art to which this device appertains.

A brief description of the operation of my device is as follows: In the utilization of this square, the blade 1 is vertically positioned against the chest contiguous to one arm of the person measured, its vertical position being ascertained by the spirit level 6. Member 3 is now swung inwardly to lie upon the shoulder with its free end disposed against the collar (that is if the person stands erect), which permits the operator to readily obtain the proper shoulder point. A tape measure one end of which is secured to the stud 12 is then carried across the chest giving the measurement of the latter all of which is plainly shown in Fig. 4.

Another tape also secured to stud 12 is extended over the shoulder and diagonally across the back to a predetermined point on a third tape depending from the center of the collar and extending down the middle of the back which we will for the sake of convenience call the back tape. To determine the point of intersection between the two tapes hereinbefore mentioned the arm 9 10 extending rearwardly from the blade 1 beneath the arm of the person being measured, has pivotally connected thereto an arm 11 intended to be swung inwardly so as to lie across the back with its outer portion projecting slightly beyond the middle thereof. When in this position the point on said arm overlying the middle of the back will be the point at which the two tapes intersect as clearly shown in Fig. 5. By the 15 foregoing the operator obtains the depth of the arm holes as well as the back measure, and he is also enabled to tell at a glance by reason of the member 3 being flush with the collar that the person measured is one having an erect carriage. However should the person be stoop shouldered then the member 3 will lie away from the collar as clearly shown in Fig. 3 and the member 11, which normally should intersect the back tape at 20 the point marked X on Fig. 3, intersects said back tape at a point at least 2 inches below said mark, designating that the back must be made a trifle large to allow for the stooped carriage of the measured person. 25 30 35 Various changes in the form, proportion and the minor details of construction may be resorted to without departing from the principle or sacrificing any of the advantages of the invention as claimed.

Having thus described my invention, what I claim is:

1. A tailor's square comprising a main

blade, a shoulder engaging member hinged to the upper end thereof and adapted to be swung laterally in either direction, said member being disposed to swing at an angle to said blade, a level arranged in said blade, and a right angular arm having a sliding adjustable engagement with the blade and having on its outer end a hinged section adapted to be swung laterally in either direction. 45 50 55

2. A tailor's square comprising a main blade, a shoulder engaging member hinged to the upper end of said blade and adapted to be swung in either direction, said member being disposed to swing at an angle to the blade 1, a level arranged in said blade, and a right angular arm having a sliding adjustable engagement with the blade and 60 having on its outer end a hinged section adapted to be swung in either direction.

3. A tailor's square comprising a main blade having therein a transverse slot, a shoulder engaging member arranged at an angle to said blade and hinged to the upper end thereof to swing in either direction, a spirit level arranged in said main blade, laterally projecting studs arranged at suitable positions on opposite sides of the main 70 blade of the square, a right angularly projecting arm having a sliding engagement with the slot in said blade, a set screw to hold said arm in its adjusted positions, and an outer member hinged to the end of said arm whereby said member may be swung in either direction. 75

In testimony whereof I have hereunto set my hand in presence of two subscribing witnesses.

VACLAV SPEVACEK.
